FRANKLYN J. WOLFF, OF TRENTON, NEW JERSEY.

METHOD OF AND MEANS FOR PRODUCING SAGGARS AND THE LIKE.

1,337,871.

Specification of Letters Patent. Patented Apr. 20, 1920.

Application filed May 19, 1919. Serial No. 293,155.

To all whom it may concern:

Be it known that I, FRANKLYN J. WOLFF, a citizen of the United States, residing at Trenton, in the county of Mercer and State 5 of New Jersey, have invented new and useful Improvements in Methods of and Means for Producing Saggars and the like, of which the following is a specification.

In the production of saggars, or fire-clay 10 cases or receptacles in which china, glass, pottery, earthen and other ware is fired, it is the usual practice to employ a grog of broken, fragmentary, or comminuted fired clay invested in a binder or vehicle of plastic or viscous clay, these materials being 15 combined in substantially equal proportions, and in order that an effective bond may be established between the ingredients of the composite substance the grog must absorb 20 a sufficient amount of moisture to exclude air and thus eliminate the possibility of blisters in firing.

Saggars are usually constructed in the form of open-topped pans or boxes, consisting 25 of a bottom and side walls, so as to enclose and protect the contained ware during the firing of the latter, while permitting the saggars to be arranged in tiers, one upon another in the kiln, and to the end that they 30 may withstand and properly distribute the intense heat of the furnace, and carry their own weight and that of their contents, without leaking (to permit the damaging access of sulfur and other fumes) and scaling or 35 cracking, it is necessary that there be a substantially even distribution of the grog throughout the bottom and walls of the structure. An excess of grog in the bottom or a deficiency thereof in the side walls 40 results in weakness, and unequal expansion and contraction due to changes of temperature, involving leakage or the dropping of particles of the bottom of one saggar upon the contents of another which injures the 45 latter by adhering thereto, and also by admitting gases which discolor and destroy the value of white ware.

The methods now generally practised in making saggars, are (1) the spreading of 50 the batch into slab form by pounding by means of a maul or otherwise on a table and (2) the forcing of the material by hydraulic pressure or its equivalent into a die or form 55 representing or conforming to the finished saggar. In the first named method the slab having been reduced to the desired thick-

ness is cut and the sides so formed are applied to a bottom of the selected dimensions, and then the structure is fired. Among the disadvantages of this method may be mentioned the slowness of the procedure, the necessity for skilled labor in reducing the batch to slabs and the lack of uniformity in the thickness and variations in the density of the slab. In the second named 60 method it is necessary to work the material in a more fluid state, forcing the mixture into that portion of the die which forms the bottom of the saggar and causing it thence to travel outward to form the side walls. 65 This procedure causes an excessive compacting of the material forming the bottom and results in an uneven distribution of the grog for the reason that the more mobile clay advancing more rapidly than the solid 70 particles of grog passes to the sides of the die to form the walls, and hence the latter 75 contain a reduced percentage of grog.

It is the object of the present invention to simplify and reduce the cost of producing 80 saggars of uniform density and even distribution of the materials throughout the bottom and walls, so as to minimize or eliminate the risk of cracking, leaking or otherwise deteriorating in use, and at the same 85 time to produce a structure of equal or greater strength and resistance to heat and weight while being itself of less weight than the saggar resulting from the old methods, and of increased and substantially calculable 90 durability.

To this end the composite plastic mixture, which may be of less fluidity than in the hydraulic method (*supra*), after having its 95 ingredients in the proper proportions thoroughly mixed and uniformly distributed, is advanced forcibly through a condensing and reducing medium which serves to spread or sheet the same, without disturbing the relations between the ingredients to produce a 100 thin homogeneous ribbon of uniform density throughout, the spreading action being effected progressively by causing the material to traverse a graduated passage affording sufficient restraint or back pressure to 105 insure a modification in the cross-sectional conformation of the stream or column of material while preserving its molecular arrangement.

In carrying out the above indicated method 110 there may be used an apparatus of which a suitable embodiment is illustrated in the ac-

companying drawings, it being understood, however, both as to the method and apparatus suggested, that various changes in form and details within the scope of the appended claims may be resorted to without departing from the principles of the invention.

In the drawings:

Figure 1 is a sectional view of that portion 10 of the apparatus which is designed to effect the mixing of the ingredients and the sheeting of the composite material, to indicate an effective and practical relation therebetween.

Fig. 2 is a sectional view in detail to show 15 the means whereby the lubricant is applied to the surface of the composite material as it is advanced through the nozzle.

Fig. 3 is a detail view in perspective of 20 the depth defining bar forming an element of the outlet of the nozzle.

Fig. 4 is a detail view of a portion of a 25 composite sheet or ribbon as it appears after it has been advanced through and discharged from the nozzle.

Fig. 5 is a diagrammatic view in perspective to illustrate the formation of a saggar 30 from the ribbon or blank as it leaves the forming mechanism.

Fig. 6 is a perspective view of another 35 form of saggar.

Essentially the method contemplated by the invention consists in effecting an intimate mixture in the proper proportions, found in practice to be substantially half and half, of solid material in fragmentary form, such as fired clay, constituting a by-product or otherwise waste material of a pottery or similar establishment, and moist or plastic clay or its equivalent; then forcibly advancing the mixture in which the solid particles are evenly distributed in the mass and are held in suspension by the plastic clay forming the vehicle or binder, through a reducing and condensing medium by 45 which, without disturbing the relations between the particles of solid material and the vehicle or binder, the stream or column is flattened progressively for ultimate discharge through a linear outlet in the form of a ribbon or sheet of the required width and thickness; conveying the sheet or ribbon as thus formed to a convenient distance from the outlet of the reducing medium; detaching portions or sections corresponding in dimensions respectively with the bottom and side walls of the proposed saggar; assembling the bottom and side wall sections while the material is still in the plastic though highly condensed and compacted condition; and finally firing the product thus assembled to produce a unitary structure.

As hereinbefore indicated it is necessary that an even and uniform distribution of 50 the solid particles constituting the filler and

consisting of fired clay or its equivalent shall be maintained throughout the procedure so as to characterize the structure of the ribbon or sheet which is the product of the reducing or condensing medium, and it 70 is further essential that there be sufficient moisture in the plastic clay constituting the vehicle or binder to afford opportunity for a sufficient absorption thereof by the particles of filler to insure the complete expulsion of air from the pores of the latter to avoid the possibility of blistering the subsequent firing operation, and in carrying out the initial step of effecting the required intimate mixture and association of the binder 80 and filler it has been found satisfactory to employ the equivalent of an ordinary pug mill such as that illustrated in Fig. 1 of the drawings and which consists of the cylindrical body 20, axially within which is arranged the shaft 21 carrying pug knives 22 and provided at its lower end with a spiral blade pusher 23 which co-operates with a worm 24 ordinarily employed as the means for advancing the mixture to the ordinary pug mill outlet 25 and from which in the ordinary practice the composite plastic mass is discharged in the form of a substantially round stream or column. 85

In the reorganization of the ordinary 90 pug mill to carry out the steps of the method of forming the substance of this invention an extension sleeve 26 may effectively be disposed in communication with the said outlet to form an entrance passage to a reducing and condensing nozzle 27, and in order to insure the continuous forcible advance of the composite plastic material through the nozzle, an additional wing and flight 28 may, as shown, be applied to the shaft 29 of the 105 worm 24, to operate within the extension sleeve 26.

The passage through the nozzle is of graduated and progressively reduced cross sectional area, the conformation being progressively modified from the substantially round inlet 30 corresponding with the outlet of the pug mill to a flat or rectilinear outlet 31 so as to insure the discharge of the composite plastic material in the form of 110 a ribbon or a sheet having a definite width and a reduced thickness determinable by the depth of the outlet 31 and variable by means of a bar 32 disposed longitudinally of the outlet, supported by shims 33 which are interchangeable to determine the relation between said bar and the lower wall of the outlet, and held in place by an angle bar 34 secured by bolts 35 or any suitable substitutes for the same. Obviously the progressively modified cross sectional conformation of the passage through the reducing nozzle serves to restrain the advance of the material and produce a back pressure which is, however, effectively opposed and over- 115 120 125 130

come by the force feed mechanism consisting in the construction illustrated of the worm, of which the additional flight 28 operating in the extension sleeve 26 serves to prevent the material which is advanced to the outlet 25 of the pug mill from being backed out of the passage and into the body of the mill. In other words, the arrangement described insures the continuous advance of the material from the plane of the pug mill outlet through the extent of the nozzle notwithstanding the restraint or back pressure exerted thereby, and as the modification in the cross sectional contour of the passageway through the nozzle is gradual and progressive, from the substantially round inlet where the mass or supply column is received to the lineal outlet where the discharge of the sheet or ribbon occurs, the mass or column is molded or transformed in such a way as to avoid any disturbance of the intimate relations between the solid and plastic ingredients consisting respectively of a filler and binder, and thus in effect preserve the molecular arrangement which has been effected in the mixing operation while in the body of the pug mill, with the result that the ribbon or sheet as it is discharged from the outlet of the nozzle is of homogeneous structure and is of uniform density throughout as well as being of accurately even thickness, so that the bottom and side wall members of the resultant saggars contain definite and predetermined proportions of both filler and binder.

As illustrated in Fig. 5 of the drawing, after the ribbon or sheet of material is received from the nozzle a suitable length thereof as indicated at A in dotted lines is wrapped, folded or rolled around a suitable form 36 (corresponding with the contour of the proposed saggars) to occupy the position shown in full lines at B, the joint at b being formed by pressing the edges of the plastic material together in the usual way, and the form or mold with the enveloping wall B formed by the blank of plastic material is arranged upon a section or blank of the plastic ribbon or sheet indicated at C in dotted lines, and after the latter has been cut around the circumference of the wall to correspond in diameter and form thereof, as indicated at D, the material at the joint is pressed together sufficiently to cause adherence, after which the article is baked or fired, all in accordance with the usual practice heretofore substantially observed in the formation of saggars and equivalent receptacles.

Owing to the resistance offered by the walls of the nozzle in the condensing and reducing process it may be found desirable under some conditions to provide for the furnishing to the surface of the advancing column of composite material a suitable lubricating agent, and to this end channeling or grooving elements 39 may be arranged in the walls of the nozzle to project into the passage of the same in the path of the column or stream of plastic material so as to produce lineal depressions or grooves therein, and these grooving elements may as shown in the drawings consist of cups designed for the reception of a lubricating oil which may be fed under pressure through the tubes 40, said cups having at their rear sides minute outlets 41. As the column of plastic material advances these grooving elements serve to produce channels in the surface of the column and in these channels is deposited the lubricating oil which owing to the moisture in the binder or vehicle does not penetrate the material, and as the channels are closed a short distance beyond the grooving elements the lubricant is spread upon the surface of the column to reduce the frictional effect and thus facilitate the advance of the column toward the outlet without diminishing the condensing and reducing effect of the passage itself upon the material. Obviously such portion of the lubricating material as remains upon the surface of the sheet or ribbon after it is discharged from the nozzle, is promptly dissipated in the subsequent firing of the product.

The invention having been described, what is claimed as new and useful is:

1. The method of producing saggars which consists in mixing a solid fragmentary filler with a plastic vehicle or binder, bodily advancing the mass thus formed through a reforming outlet to produce a continuous sheet or ribbon, detaching and removing from the path of the sheet or ribbon, independent sections of proportional dimensions to form the bottom and walls of the product and finally assembling and firing the same.
2. The method of producing saggars which consists in mixing a fragmentary filler of solid material with a plastic vehicle or binder, bodily advancing the mass through a reforming and condensing passage to produce a continuous flat sheet or ribbon, detaching and removing sections of the sheet or ribbon thus formed, and finally assembling to form a saggars structure and firing the same.
3. The method of producing saggars which consists in mixing a fragmentary filler of moisture absorbent solid material with a plastic vehicle or binder, bodily advancing the mass through a reforming and condensing medium to discharge the same in the form of a sheet or ribbon, detaching and removing sections of the sheet or ribbon, assembling to form a saggars structure and finally firing the same.
4. The method of producing saggars which consists in mixing a solid fragmentary filler

with a plastic binder, bodily advancing the mass through a reforming passage to a sheet forming outlet to produce a continuous ribbon, detaching and removing from the path of the ribbon, independent sections of proportional dimensions to form the bottom and walls of the product and finally assembling and firing the same.

5. The method of producing saggars which 10 consists in reducing a composite mass of intimately mixed solid and plastic materials to a sheet by forcibly advancing the same through a progressively modified condensing and reforming passage terminating in a 15 lineal outlet of uniform depth and subsequently detaching bottom and wall sections from the sheet, assembling said sections, and finally firing the same.

6. The method of producing saggars which 20 consists in mixing a fragmentary filler of solid material with a plastic vehicle or binder, bodily advancing the mass through a reforming medium to discharge the same in the form of a sheet or ribbon, detaching and 25 removing sections of the sheet or ribbon, assembling the sections to form a sagger structure and finally firing the same.

7. The method of producing a homogeneous ribbon of composite material having 30 solid particles in suspension in a plastic vehicle which consists in forcibly advancing the mass after mixture through a progressively modified reducing and condensing

medium, continuously and intermediately channeling the surfaces of the advancing 35 column, and applying a lubricant to the channels thus formed.

8. An apparatus for the purpose named having a force feed mechanism and a reducing nozzle for receiving plastic material 40 therefrom, the said nozzle having internal channel forming elements and associated lubricant feeding means.

9. In the production of saggars for use in firing pottery and the like, and wherein the walls and bottom are composed of a substantially fired mixture of a plastic vehicle or binder in which is incorporated a fragmentary filler of solid material, and wherein a uniform distribution of the fragmentary 50 filler throughout the body of the walls and bottom is desired, the method of forming a sheet or strip from which said walls and bottom may be cut, which consists in thoroughly mixing said vehicle or binder and 55 filler to secure the said uniform distribution of the latter throughout the mass and then advancing the mass, under pressure, through a progressively modified shape transforming passage to a transversely elongated outlet of 60 a depth determining the thickness of the sheet or ribbon.

In testimony whereof I affix my signature.

FRANKLYN J. WOLFF.
